UNITED STATES PATENT OFFICE.

ALVA B. SMITH, OF ST. LOUIS, MISSOURI, ASSIGNOR, BY DIRECT AND MESNE ASSIGNMENTS, OF ONE-HALF TO JOHN T. O'CONNOR, OF ST. LOUIS, MISSOURI, AND ONE-HALF TO JAMES M. GRAY, OF WEBSTER GROVES, MISSOURI.

CLASP SUSPENDER FOR TROUSERS AND THE LIKE.

Application filed January 19, 1923. Serial No. 613,637.

To all whom it may concern:

Be it known that I, ALVA B. SMITH, a citizen of the United States, residing at the city of St. Louis, State of Missouri, have invented a certain new and useful Clasp Suspender for Trousers and the like, of which the following is a specification, reference being had to the accompanying drawing, forming a part thereof.

10 This invention relates generally to trouser-supporting devices and, more particularly, to a certain new and useful so-called clasp-suspender for trousers and the like, the chief objects of my present invention being to provide a simple, inexpensive, and durable clasp which is readily operatively attachable to the shirt or other garment and with and from which a trouser-button may be easily and conveniently engaged 15 and disengaged, and which will hold the trousers up and the shirt or other garment down in an efficient, neat manner, without injury to the shirt or other garment and affording comfort and freedom of movement 20 to the body, and to improve generally upon and simplify the construction of devices of the kind stated.

With the above and other objects in view, my present invention resides in the 30 novel features of form, construction, arrangement, and combination of parts hereinafter described and afterwards pointed out in the claims.

In the accompanying drawing, 35 Figure 1 is a front elevational view of what I may designate the main member of the clasp;

Figure 2 is a side edge view of the same; Figure 3 is an elevational view of the 40 clamping-frame of the clasp;

Figure 4 is a perspective view of form of trouser-button adapted preferably for use in connection with the clasp;

Figure 5 is a longitudinal sectional view 45 of the clasp as when operatively attached upon a garment and in engagement with such trouser-button; and

Figure 6 is a diagrammatical view of 50 the clasp, illustrating the operation of disengaging the clamping-frame from the main member of the clasp to detach or release the clasp from a garment.

Referring now more particularly to the said drawing, in which like reference char-

acters refer to like parts throughout the several views, my present clasp-suspender comprises a so-called main member A, which is preferably in the form of a relatively small, rectangular plate 1 suitably formed at its upper and lower margins by die pressing or otherwise, with a pair of oppositely disposed lips 2 and 3, respectively, which are offset rearwardly from, but which both extend vertically in a plane approximately parallel with the plane of, the major portion or body 1 of the plate. The lips 2 and 3 so provided form with the rearwardly offset or flange-extensions 4 and 5 of the plate a seat at the upper and lower ends of the plate 1 for the co-operating clamping-member or frame B of the clasp; and to facilitate the engagement with, and disengagement from, the member A of the frame B, the lower lip 3 is preferably of somewhat less width than upper lip 2, as seen especially in Figure 5. Within its area, as best seen in Figure 1, body 1 of the plate is kerfed, as at 6-7, and the central portion 8 thereof then die-pressed or otherwise manipulated inwardly or rearwardly out of the general flat plane of the body 1 of the plate to form or provide the plate with what I may descriptively designate an open-end pocket for receiving and accommodating a trouser-button.

It will be noted that the body 1 of the plate A is extended at its opposite side margins, as at 9, 9, and thereby adapted for co-operation with the upper and lower lips 2 and 3 in holding or locking the frame B securely, but detachably, to its described seat.

The clamping-frame B before mentioned is, as shown, a substantially rectangular open or skeleton frame of suitable material and is of a size relatively to member A to embrace the opposite upper and lower margins thereof and snugly, but removably, fit, when in clamping engagement with and upon the member A, upon its described seat and behind the projecting extensions of body 1 of the plate.

Adapted for co-operation with the clasp, is a so-called button C comprising a plate 10, punched or otherwise provided upon which is a head 11 undercut or grooved upon its opposite sides, as at 12, for reception in, and engagement with the walls of, the described pocket of the clasp. The button

C is, in practice, disposed flatwise at its plate 10 upon the trousers at the waist thereof, with head 11 disposed inwardly, the plate 10 being suitably perforated, as at 13, 5 to accommodate securing thread.

In use or operation, and first in attaching the clasp operatively, for instance, upon a shirt, the frame B is placed flatwise upon the inner surface of the material of the shirt 10 and at the location desired, usually along the waist-portion of the shirt. The member A is now placed more or less obliquely upon the outer surface of the material of the shirt and its upper and somewhat longer 15 lip 2 projected or inserted endwise into the frame and beneath the upper cross member thereof. The member A is then swingably pressed downwardly to lie flatwise upon the outer surface of the material of the shirt, 20 and its lower lip 3, in such movement, forced into and through the opening of the frame B.

The member A is now slightly endwise moved downwardly relatively to frame B, 25 and the frame B, in and by such operations or movements of the member A, forced to its said seat upon the member A, with the lips 2, 3 disposed under the frame and to and upon which seat the frame B is now 30 securely held or locked by the outwardly projected or extended side edge-portions 9 of the body 1 of the plate. It being understood that in such operations the frame B and the member A are disposed upon the 35 opposite surfaces of the shirt, it will at once be seen that portions or folds of the shirt, as at 14 and 15, are in such operations clamped at the said lips 2 and 3 and offsets 4 and 5 between the frame B and member 40 A, frame B and member A being thus as described securely, but detachably, locked together and in firmly clasped attachment upon the shirt.

With the clasp so attached as described 45 upon the shirt or other garment, the described pocket of the clasp is disposed substantially flatwise upon the garment and conveniently accessible for engagement with, or disengagement from, a trouser-button, 50 such, for instance, as the head 11 of plate 10 illustrated in Figure 4, the head or button 11 being conveniently as desired slipped into or out of the pocket by the wearer.

My present suspender-clasp may be inexpensively manufactured, is most conveniently and easily attachable upon a shirt or other garment, provides when upon the shirt or other garment a convenient means for quick and ready attachment or detachment 60 of a trouser supporting-button, and in use will hold the trousers up and the shirt or other garment down in a most simple, neat, and efficient manner, without injury to the shirt and at the same time affording comfort and freedom of movement to the user,

The depressed plate-portion 8, providing somewhat of a rear wall for the button-pocket of member A, serves also to prevent the button or head 11 injuriously contacting or rubbing against the shirt or other 70 garment.

As diagrammatically illustrated in Figure 6, the clasp may be readily detached from the shirt or other garment whenever required by a reversal of the operations 75 above described, upward movement of member A relatively to frame B and then a swinging movement of member A relatively to frame B, as indicated by the arrows, unseating the frame B and member A and frame B being then conveniently, as shown, 80 disengaged one from the other and the clasp as a whole detached or removed from the shirt.

I am aware that changes in the form, construction, arrangement, and combination of the several parts of the clasp may be made and substituted for those herein shown and described without departing from the nature and principle of my invention. 85

Having thus described my invention, what I claim and desire to secure by Letters Patent is:

1. As a new article of manufacture, a 90 clasp-suspender including, in combination, a skeleton frame and a separate marginally flanged plate-member having oppositely-presented offset lips and an open-end pocket for receiving and accommodating a trouser-supporting button, the frame being adapted to embrace the opposite margins of the plate and the plate-member being engageable at said lips under the frame for gripping the garment therebetween in detachably fastening the button-pocket flatwise upon the 95 garment. 100

2. As a new article of manufacture, a 105 clasp-suspender including, in combination, a skeleton frame and a separate plate-member provided at opposite margins with lateral flanges and oppositely presented offset lips and having intermediate the lips an open-end pocket for receiving and accommodating a trouser-supporting button, the frame being 110 adapted to embrace the opposite margins of the plate at said flanges and the plate-member being insertable at said lips within the frame and endwise engageable at said lips under certain members of the frame for gripping the garment therebetween in detachably fastening the button-pocket flatwise upon the 115 garment. 120

3. As a new article of manufacture, a 125 clasp-suspender including, in combination, a skeleton frame, a separate plate-member provided at opposite margins with lateral flanges and oppositely presented offset lips and having intermediate the lips an open-end pocket for receiving and accommodating a trouser-supporting button, the frame being 130

adapted to embrace the opposite margins of the plate at said flange and the plate-member being insertable at said lips within the frame and endwise engageable at said lips under certain members of the frame for gripping the garment therebetween in detachably fastening the button-pocket flatwise upon the garment, and extensions upon

the plate at its other opposite margins adapted to project in frame-holding engagement over other members of the frame when the plate and frame are in interengaging relation. ¹⁰

In testimony whereof, I have signed my name to this specification.

ALVA B. SMITH.
